UNITED STATES PATENT OFFICE.

THOMAS LONET, OF OAKLAND, CALIFORNIA.

DESIGN FOR AN AUTOMOBILE SIGNAL-LIGHT CASING.

Application filed March 19, 1923. Serial No. 5,537. Term of patent 3½ years.

To all whom it may concern:

Be it known that I, THOMAS LONET, a citizen of the United States, resident of Oakland, in the county of Alameda and State of California, have invented a new, original, and ornamental Design for an Automobile Signal-Light Casing, of which the following is a specification, reference being had to the accompanying drawing, forming a part thereof.

Figure 1 is a perspective view of the automobile signal light casing, showing my new design.

Figure 2 is a rear elevation of the same.

I claim:

The ornamental design for an automobile signal light casing, as shown.

THOMAS LONET.
